UNITED STATES PATENT OFFICE

MALCOLM H. TUTTLE, OF NEW ROCHELLE, NEW YORK

PROCESS FOR SEPARATION OF MINERAL OIL

No Drawing.

Application filed December 22, 1932. Serial No. 648,382.

This invention relates to a process for the separation of mineral oil into fractions which are respectively more paraffinic in composition and characteristics and more naphthenic in composition and characteristics than is the original oil and which may have similar boiling ranges.

Mineral oils comprise naphthenic constituents and paraffinic constituents which have different characteristics that are known to a considerable extent; and these constituents impress their characteristics upon the oil to a degree depending upon the proportion in which they are present in the oil. Oils comprising a relatively higher proportion of paraffinic constituents are commonly called paraffinic base oils, an example thereof being oils from the Pennsylvania field; and oils containing a relatively lower proportion of paraffinic constituents and therefore a relatively higher proportion of naphthenic constituents are commonly called naphthenic or asphaltic base oils, an example of such oils being oils obtained from Gulf Coastal or Mexican fields; and oils containing an intermediate proportion of paraffinic constituents and also containing naphthenic constituents are commonly called mixed base oils, an example of such oils being oils from the mid-continent fields.

Paraffinic oils having a given viscosity have a lower specific gravity, a higher flash test, a smaller change of viscosity in changes in temperature and a higher ratio of hydrogen to carbon than do naphthenic oils of the same viscosity. Paraffinic oils are more stable and more desirable as lubricants, particularly under conditions involving high temperatures and extensive changes of temperature than are oils in which paraffinic constituents are present in relatively lower proportion and naphthenic constituents are present in relatively high proportion. The characteristics of mid-continent or mixed base oils are intermediate the characteristics of paraffin base and asphalt base oils.

Naphthenic oils are preferable to paraffinic oils for some uses, such as insulating oils for electrical apparatus and lubrication of chains and of gearing not subjected to low temperatures. In other words, the effects of a high

or increased proportion of paraffinic constituents of an oil are known and the uses in which such oils are preferable are known; and the characteristics imparted to oil by a high or increased proportion of naphthenic constituents are known, and the uses in which such oils are preferable are known.

An object of this invention is to provide a process whereby mineral oils may be rapidly and economically separated into fractions which are respectively more paraffinic and more naphthenic than the original oil, the separation being effected regardless of whether the oil has previously been subjected to acid treatment and without chemical reaction and without formation of sludge, to the end that solvents employed to effect such separation may be used indefinitely and losses minimized.

A specific object of this invention is to provide a method whereby oils obtained from mixed base petroleum may be separated into fractions of which at least one is a lubricating oil stock having viscosity-gravity characteristics and viscosity-temperature characteristics similar to or equal to or better than such characteristics of oil stocks having similar viscosity and obtained by usual distillation from crude oils from the Pennsylvania field.

To assist in understanding the effects and results of the practice of this invention, reference may be made to certain values commonly employed to indicate the character of oil. Thus the relation of viscosity to specific gravity is indicated by the viscosity-gravity constant determined in accordance with the following equation.

$$a = \frac{G - 0.24 - 0.022 \log (V' - 35.5)}{0.775} \quad 90$$

where a = viscosity-gravity constant

V' = Saybolt viscosity at 210° F. 95

G = specific gravity at 60° F.

Pennsylvania lubricating oils have a viscosity-gravity constant falling between approximately .807 and .827; mixed base Mid-Continent lubricating oils have a viscosity-grav-

100

ity constant falling between approximately .827 and .867; and naphthenic or asphalt base lubricating oils from the Gulf coast and California have a viscosity-gravity constant falling between approximately .867 and .887. However, specific oils from one field will have a viscosity-gravity constant falling within the range above given for another field. Moreover, the relation of temperature to viscosity is measured by a viscosity index in which Pennsylvania oils have a value of 90 to 100 and oils of lower viscosity index are less paraffinic and the oils of higher viscosity index are more paraffinic. Herein the expression naphthenic constituents includes asphalts and mixtures of asphalts and naphthenic oils.

In accordance with this invention, mineral oils are separated into fractions which are respectively more paraffinic and more naphthenic than the original oil, by subjecting the oil to fractional extraction with wood tar acids which are later removed from the fractions so produced. The wood tar acids have greater solvent power for naphthenic constituents than for paraffinic constituents of the oil, and the extracting solvent takes up a markedly greater proportion of naphthenic constituents than it does of paraffinic constituents; and the solution separates from the remainder of the oil and forms a lower layer. The upper layer comprises the remainder of the oil and contains some of the solvent but is markedly richer in paraffinic constituents than is the original oil.

In accordance with this invention, the treatment of the oil with wood tar acids can be a batch operation, and in such case the upper layer may be removed and contacted again with the solvent, such operation being repeated any desired number of times until the oil contained in the final upper layer possesses the desired characteristics. Or, in the practice of this invention, the procedure may be continuous, as by maintaining a countercurrent flow of oil to be treated and extracting solvent, in such case the countercurrent flow of oil and solvent in contact being of such extent or being repeated a sufficient number of times to cause the paraffinic fraction so obtained to possess the desired characteristics.

Wood tar acids which are suitable for the practice of this invention are obtainable in the open market and are usually acids obtained from the tars of harder woods, the tars of softer woods usually containing too little of wood tar acids to justify the recovery thereof from the tar. Ordinarily, but not necessarily, the wood tar acids are recovered from the wood tars by treating the tar with an aqueous solution of caustic soda and then acidulating the resulting aqueous product. A specific example of wood tar acids which has been found to be highly effective in the

practice of this invention is a mixture of wood tar acids commercially known as beechwood creosote. Wood tar acids, of which beechwood creosote is an example, are composed chiefly of orthocresol, guaiacol (mono-methylcathechol), and cresol; and it is contemplated that, in the practice of this invention, commercial wood tar acids or the separate ingredients thereof or mixtures of such ingredients may be employed. 75

In the practice of this invention, the proportion of wood tar acids to oil treated may be varied within a considerable range, for example, one to three parts or more by weight of solvent being employed for each part of oil treated, it being advisable that the optimum ratio of solvent to oil be determined by test.

In the practice of this invention, the oil is contacted with the wood tar acid or acids at such temperature as will promote the solution of naphthenic constituents in the solvent employed, and the contacting of the oil and solvent is effected at, or the mixture is brought to, a temperature which promotes separation of the mixture into distinct layers. Lower temperatures favor the formation of distinct layers and increase the selectivity of the solvent for naphthenic constituents. Advantageous features of the use of wood tar acids are that they are not likely to solidify at temperatures as low as 20° F. and an effective separation into layers occurs at temperatures as high as 100° F. to 160° F. In the treatment of wax-containing oil, the mixture of wood tar acid and oil should at some time before separation possess a temperature at which the wax is all in liquid state; but the separation of the layers is usually promoted by lowering of the temperature and it may be made thereafter at a temperature at which a part of the wax is solidified. An advantage of the use of wood tar acids is that with some Mid-Continent oils all steps of the treatment, including separation, may be performed at a temperature at which all of the wax is in liquid state. Another advantageous feature of the use of wood tar acids is that they may be separated completely from oils having an initial boiling point not substantially lower than 450° F., by distillation at temperatures far below temperatures which would tend to decompose either the oil or the solvent. For example, at 10 mm. absolute pressure, the wood tar acids can be separated completely from oil at temperatures not substantially in excess of 425° F. The maximum boiling point of wood tar acids does not ordinarily exceed 225° F. at 10 mm. absolute pressure, and the use of temperatures as high as 425° at 10 mm. absolute pressure effects complete removal of the wood tar acids from the oil and any oil vaporized may be refluxed from the vapors evolved.

In the practice of this invention, treatment 130

with wood tar acids may be applied to oils having a final boiling point below the initial boiling point of the solvent, in which case the oil is distilled off of the mixture, leaving the solvent as a residue. Oil constituents having boiling points within the boiling range of the solvent cannot readily be separated from the solvent by distillation, but only by treatment of the mixture with aqueous alkaline 10 solutions.

In accordance with this invention, the oil is contacted with a chosen wood tar acid or mixture of wood tar acids at a temperature sufficiently high to effect extensive solution 15 of the naphthenic constituents in solvent but sufficiently low to prevent decomposition, and the oil is allowed to form in two layers at a temperature sufficiently low to promote such layer formation but not so low as to effect 20 solidification of the solvent. The layers ultimately so formed are separated by decantation and the solvent is removed from both layers. The more paraffinic fraction so formed will possess to a more marked degree than does the original oil those characteristics imparted to oil by paraffinic constituents; and similarly the more naphthenic 25 fraction will possess to a more marked degree than does the original oil those characteristics 30 imparted to oil by naphthenic constituents. In this manner, the practice of my invention enables the production from Mid-Continent oils and from more naphthenic or asphaltic oils, such as Coastal or California oils, of an 35 oil having a viscosity-gravity constant and a viscosity-temperature index equal to or better than those characteristics of oils obtained 40 from the Pennsylvania field.

As a specific example, an oil obtained from 45 Mid-Continent mixed base crude oil and having a specific gravity of 0.9236, a Saybolt universal viscosity of 148 seconds at 210° F., and a viscosity-gravity constant of 0.845 was treated in a continuous counter-current flow system 50 with 150% by weight of beechwood creosote at 100° F., and the more paraffinic fraction, after removal of the solvent, had a specific gravity of 0.8944, a Saybolt Universal viscosity of 112 seconds at 210° F. and a viscosity-gravity constant of 0.812, and, by volume, was 52.4% of the original oil. The more naphthenic fraction produced in that procedure had, after removal of the solvent, a specific gravity of 0.9550, a Saybolt Universal viscosity of 206 seconds at 210° F. and a viscosity-gravity constant of 0.880.

In the practice of this invention, an extending of continuous counter-flow or a repetition thereof or a repetition of bath extraction treatments results in a further increase of the differences between the characteristics of the original oil and the characteristics of the respective resulting fractions.

The solvent recovered from the ultimate

upper and lower layers, i. e., from the ultimate paraffinic and naphthenic fractions, may be repeatedly employed.

The ultimate paraffinic and naphthenic fractions may be subjected to such further treatment as may be desirable, such as usual refining steps including acid treatment and clay treatment or contact filtration and dewaxing, in order to produce finished products. In such case, the finished products obtained from the paraffinic fraction may readily be caused to possess characteristics comparable to or better than the characteristics of Pennsylvania oils.

A further feature of this invention is that in the contacting of the oil with wood tar acids or components thereof, at least some part of the contacting may be effected in the presence of a solvent having greater solvent power for paraffinic constituents than for naphthenic constituents, such simultaneous contacting of the oil with a paraffinic solvent and with a naphthenic solvent being preferably carried out under such conditions that the solvents employed are mutually miscible to only a limited extent. Examples of solvents having selective solvent power for paraffinic constituents are ethane, propane, butane, pentane, petroleum ether, natural gasoline, and 300° F. endpoint Pennsylvania gasoline. When using gasoline obtained from petroleum, the selective solvent power thereof for paraffinic constituents may be improved or insured by preliminarily subjecting the gasoline to extraction with wood tar acids or components thereof or other solvents having selective solvent power for naphthenic constituents. In the contacting of the oil simultaneously with two solvents, the contacting is effected under conditions which insure that at some time in the contacting operation prior to the separation operation all constituents of the mixture will be in liquid phase. Just as lower temperatures favor the formation of separate layers when a solvent having selective solvent power for naphthenic constituents is employed alone, so do lower temperatures favor the formation of layers between naphthenic and paraffinic solvents used simultaneously and containing oil constituents in solution.

Procedure wherein paraffinic and naphthenic solvents are simultaneously employed, and the advantages thereof, are more at length set out in my co-pending application, Serial No. 623,483, filed July 20, 1932. It is contemplated that naphthenic and paraffinic solvents may be simultaneously employed in either a batch procedure or a continuous procedure. As more fully set out in said application, the presence of the paraffin solvent results in more effective operation of the naphthenic solvent, either by satisfying the solvent power of the naph-

thenic solvent for paraffinic constituents or by displacing from the naphthenic solvent, or from the mixture of naphthenic solvent and constituents dissolved thereby, paraffinic constituents which are desired in the paraffinic fraction.

The oil may be brought directly into simultaneous contact with both wood tar acid and a paraffinic solvent, and the resulting layers separated and freed of solvents. Or, the oil 10 may first be contacted with wood tar acid and the separation of layers made in the usual way and the upper layer freed of solvent to provide the desired paraffinic fraction. But, 15 the naphthenic layer is then contacted with the paraffinic solvent and the resulting lower layer is freed of solvents to provide the desired naphthenic oil while the resulting upper fraction comprising paraffinic constituents and solvent and wood tar acid is freed 20 of such solvent and added to the oil passing to the first contacting step. Thus the oil passing to the first contacting step is rendered more paraffinic than the raw charging 25 stock and gives a greater ultimate yield of paraffinic oil, the added paraffinic oil constituting an additional recovery of paraffinic oil from the naphthenic fraction and assisting in promoting separation, especially in the dividing of highly naphthenic oils.

Moreover, it is contemplated that the effectiveness of wood tar acids or components thereof as naphthenic solvents may be increased by mixing with the wood tar acids 30 or components thereof a suitable proportion 35 of sulphur dioxide, and effecting the extraction under conditions which maintain the sulphur dioxide in solution in the naphthenic solvent. The sulphur dioxide has a distinct selectivity for naphthenic constituents 40 and for asphalt and for constituents of higher molecular weight but it has limited solvent power for oil constituents and is not soluble in all proportions in oils of high asphalt content as are nitro-aromatic solvents.

Other similar substances are furfural, aniline, and pyridine.

The efficiency of the operation is substantially improved by treatment of the oil with the wood tar acids used as naphthenic solvents 50 in the presence of a paraffinic solvent. For example, a repetition of the specific example above set forth, using 200% by weight of beechwood creosote and 200% by weight of propane and performing the contacting and 55 separating at a temperature of 24° F. under a gage pressure in excess of 45 lbs. per square inch, gave a naphthenic fraction, freed of solvents, having a specific gravity of 0.9950, a Saybolt Universal viscosity of 452 seconds 60 at 210° F., and a viscosity-gravity constant of 0.924. The paraffinic fraction produced as a result of the simultaneous use of the two solvents had substantially the same characteristics as the paraffinic fraction produced 65 by the use of the beechwood creosote alone,

and it constituted 69.8% of the original oil and was about 33% by volume greater than the paraffinic fraction produced by the use of beechwood creosote alone.

It is contemplated that distillates and residues, refined or unrefined, may be treated in accordance with this invention, this invention being of special importance in the treatment of lubricating oils for the improvement of the characteristics thereof.

It is understood that this invention is not to be limited by any theory of operation expressed nor by any example given, and that it includes all modifications and variations falling within the appended claims.

I claim:

1. In the art of separating mineral oil into its paraffinic and naphthenic constituents, the step comprising extracting the oil with a wood tar acid.

2. In the art of separating mineral oil into its paraffinic and naphthenic constituents, the step comprising extracting the oil with a mixture of wood tar acids.

3. In the art of separating mineral oil into its paraffinic and naphthenic constituents, the step comprising extracting the oil with beechwood creosote.

4. In the art of separating mineral oil into its paraffinic and naphthenic constituents, the step comprising extracting the oil with a solvent containing a substantial proportion of one of the substances consisting of guaiacol, creosol, beechwood creosote, and a mixture of two or more thereof.

5. In the art of separating mineral oil into its paraffinic and naphthenic constituents, the steps comprising contacting mineral oil containing paraffinic and naphthenic hydrocarbons with a solvent containing a wood tar acid under conditions causing separation of the mixture into layers, separating the upper layer from the lower layer, and removing the acid from the upper layer.

6. In the production of lubricating oil the step comprising extracting a lubricating oil fraction of petroleum with a solvent containing a wood tar acid.

7. In the production of lubricating oil the step comprising extracting a lubricating oil fraction of Mid-Continent petroleum with a solvent containing a wood tar acid.

8. In a process for separating mineral oil containing paraffinic and naphthenic constituents into fractions respectively more paraffinic and more naphthenic than the original oil, the step comprising contacting the oil with wood tar acid.

9. In a process for separating mineral oil containing paraffinic and naphthenic constituents into fractions respectively more paraffinic and more naphthenic than the original oil, the step comprising contacting the oil with beechwood creosote.

10. In the art of refining mineral oil, the

steps comprising contacting mineral oil containing paraffinic and naphthenic hydrocarbons simultaneously with a solvent containing a wood tar acid and with a low-boiling 5 paraffin solvent under conditions causing separation of the mixture into layers, and separating the resulting layers.

11. In a process for separating oil containing paraffinic and naphthenic constituents 10 into fractions respectively more paraffinic and more naphthenic than the original oil, the steps comprising contacting the oil, in the presence of an added liquid having greater solvent power for paraffinic constituents 15 than for naphthenic constituents, with a liquid comprising a wood tar acid.

12. In a process for separating oil containing paraffinic and naphthenic constituents 20 into fractions respectively more paraffinic and more naphthenic than the original oil, the steps comprising contacting the oil, in the presence of an added liquid having greater solvent power for paraffinic constituents 25 than for naphthenic constituents, with beechwood creosote.

13. In the art of refining mineral oil, the step comprising extracting the oil with a mixture of wood tar acid and sulphur dioxide.

14. In the art of refining mineral oil, the 30 step comprising extracting the oil with a mixture of wood tar acid and one of the group comprising sulphur dioxide, pyridine, furfural, analine, and a mixture of two or more thereof.

35 15. In the art of refining mineral oil, the steps comprising bringing mineral oil having an initial boiling point not substantially below 450° F. into contact with wood tar acid and thereby effecting a solution in the wood tar acid of a portion of the oil richer 40 in naphthenic constituents than is the original oil, separating the solution from the remainder of the oil, and distilling the wood tar acid from the remainder of the oil.

45 16. In the production of lubricating oil, the steps comprising contacting a residue, having a flash point not substantially less than 450° F. and obtained from Mid-Continent petroleum, with wood tar acid, whereby 50 to form two liquid layers, the upper of said layers containing the naphthenic constituents of the residue separating the resulting layers, and removing wood tar acid from the upper layer.

55 17. In the art of refining mineral oil comprising naphthenic and paraffinic constituents, the steps comprising contacting the oil with wood tar acid, and contacting the solution 60 of oil constituents in wood tar acid with a solvent having greater solvent power for paraffinic than for naphthenic constituents of the oil.

18. In the art of refining mineral oil comprising naphthenic and paraffinic constituents, the steps comprising contacting the oil

with a solvent having greater solvent power for paraffinic than for naphthenic constituents of the oil, and contacting the solvent and the oil constituents dissolved therein with wood tar acid.

70 19. In the art of refining mineral oil comprising naphthenic and paraffinic constituents, the steps comprising contacting the oil with wood tar acid, contacting the solution of oil constituents in wood tar acid with a 75 solvent having greater solvent power for paraffinic than for naphthenic constituents of the oil, separating the solvent and substances in solution therein from the remainder of the solution of oil constituents in wood tar acid, removing the solvent from said substances in solution therein, and passing the substances to the oil passing to the first-mentioned contacting step.

80 20. In the art of refining mineral oil comprising naphthenic and paraffinic constituents, the steps comprising contacting the oil with wood tar acid, contacting the solution of oil constituents in wood tar acid with a solvent having greater solvent power for paraffinic than for naphthenic constituents of the oil, and passing the solvent and oil dissolved 85 therein into the first-mentioned contacting step.

90 21. In the art of separating mineral oil into its paraffinic and naphthenic constituents, the steps comprising contacting the oil with wood tar acid and thereafter contacting the solution of oil constituents in wood tar acid with a paraffinic solvent of the group comprising 95 any or all of ethane, propane, butane, pentane, petroleum oil, natural gasoline or 300° F. Pennsylvania gasoline.

100 22. In the art of refining mineral oil, the steps comprising extracting the oil with a mixture of wood tar acid and one of the group comprising sulphur dioxide, furfural, analine or a mixture of two or more thereof, and simultaneously subjecting the said oil to the action of a paraffinic solvent of the group 105 comprising any or all of ethane, propane, butane, pentane, petroleum oil, natural gasoline or 300° F. Pennsylvania gasoline.

110 In testimony whereof, I have signed my name to this specification.
